US0D1053589S

(12) **United States Design Patent** (10) Patent No.: **US D1,053,589 S**
(45) Date of Patent: ** Dec. 10, 2024

(54) **STORAGE RACK FOR ELECTRIC TOOL**

(71) Applicant: **Xiaomei Zhao**, Laixi (CN)

(72) Inventor: **Xiaomei Zhao**, Laixi (CN)

(**) Term: **15 Years**

(21) Appl. No.: **29/949,369**

(22) Filed: **Jun. 26, 2024**

(51) LOC (14) Cl. **08-08**

(52) U.S. Cl.

USPC **D6/570**; D6/675.1

(57) **CLAIM**

The ornamental design for a storage rack for electric tool as shown and described.

DESCRIPTION

FIG. 1 is a perspective view of a storage rack for electric tool showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines in the drawings are for the purpose of illustrating portions of the storage rack for electric tool and form no part of the claimed design.

1 Claim, 8 Drawing Sheets
